UNITED STATES PATENT OFFICE

2,638,004

COMBINED FRICTION DRIVE AND DETENT

Robert L. Boyles, Framingham, Mass., assignor
to General Electric Company, a corporation of
New York

Application February 15, 1952, Serial No. 271,833

4 Claims. (Cl. 74—207)

1

My invention relates to a combined clutch, friction drive and detent mechanism. It will be explained for the purpose of operating a switch and as thus used may be considered to represent an improvement on the so-called sleep switch described in United States Patent No. 2,505,573, to Prophet, April 25, 1950, assigned to the same assignee as the present invention. The patent mentioned describes time switch mechanism for controlling a radio and the like, and includes a switch associated with a timing device by means of which a person may turn the radio on for a predetermined adjustable period, the switch to be opened and the radio to be turned off automatically at the end of such period. According to my invention, I provide a friction drive switch control means which also serves as a clutch and a detent by means of which the person turning the switch on may set the "on" timing period approximately by feel in the dark or without looking at the control means.

The features of my invention which are believed to be novel and patentable will be pointed out in the claims appended hereto. For a better understanding of my invention reference is made in the following description to the accompanying drawing in which Fig. 1 represents a face view partially in section of my invention as applied to a time switch. Fig. 2 shows a side view of the friction drive of my invention. Fig. 3 is a face view of the friction drive member showing the detents therein, and Fig. 4 is a perspective exploded view of the application of my invention to a time switch mechanism of the character represented in Fig. 1.

In Fig. 1 there is represented a portion of a clock face 5 with the usual time telling hands. To the rear of the dial there is a switch having upper and lower resiliently supported contacts 6 and 7 leading to terminals at 8 (see also Fig. 4), and by means of which a circuit such as a radio circuit in which the switch is connected may be opened and closed. The lower switch contact may be pressed downward and allowed to rise again to open and close the switch by the finger 9 of an actuator made of insulating material and rotatable about or with the rod 10. This actuator is operated automatically to close the switch under certain conditions at a predetermined time by mechanism, not shown, but which may be similar to that shown in the previously mentioned Patent No. 2,505,573. The actuator also has a finger 9a engageable by a part 11 of a rotatable manual control to open the switch when such manual control is in the rotary position represented in Fig. 1. The manual control

2

part may be rotated further clockwise to cause a cam portion 12 thereof to engage an arm 13 fastened to the upper contact 6 and press such contact downward to close the switch. The manual control has a third position, counterclockwise from the position shown in Fig. 1, where neither parts 11 nor 12 interfere with the operation of the switch such that it may be open or closed, depending upon the position of the actuator finger 9 and the manual control of my invention. A spring 14 engages a detent member 15 on the shaft of actuator 11 to determine the three positions of such shaft.

Ordinarily, when a person retires at night, the switch is held open by finger 9 pressing down on contact 7. Under these circumstances it often happens that the user will wish to have the switch closed and the radio operating while he or she is dropping off to sleep and have the switch open automatically and the radio cut off in a relatively short time, such as 15, 30, 45 or 60 minutes, and to accomplish this without disturbing the setting of other controls of the switch, such as the parts 9, 9a and 12. It is the primary purpose of the control of my invention to enable the apparatus to be used for this latter purpose as also is the purpose of the so-called sleep switch feature of the above-mentioned patent. My invention represents an improvement in this feature in that it uses fewer parts and has the advantage that it can be set in the dark, or without looking at it, to approximately the desired radio operating time.

The sleep switch feature includes the lever 16 pivoted on rod 10 and having one end 17 positioned to engage an insulating arm 18 secured to top resilient switch contact member 6, and its other end 19 in engaging relation with a cam 20 which constitutes a part of the friction detent drive.

The cam 20 is securely fastened to a shaft 21 which is provided at the front of the clock with a button 22 by means of which the shaft 21 and cam 20 may be manually turned. The button 22 on shaft 21 is preferably provided with an index 23 indicating on a scale 24 to show the adjusted position of shaft 21 and cam 20. The cam has an upper sector portion 25 having a peripheral surface generally circular with respect to the shaft 21 as a center, which surface is in frictional driving relation with a grooved friction wheel 26 integral with a pinion gear 27 on a shaft 28. It is immaterial whether the parts 26 and 27 rotate on shaft 28 or are fastened to the shaft and the shaft is made rotatable.

Gear 27 is in mesh with a gear 29 which is continuously driven by the clock in a counterclockwise direction and at a speed suitable for the purpose intended. I provide means for resiliently maintaining the engaging surfaces of sector 25 and wheel 26 in firm engagement. For instance, one of the shafts 28 or 21 may be resiliently biased toward the other, or the sector 25 may be made of relatively thin resilient material and have an offset as shown, so as to have sufficient radial resiliency to maintain firm contact with wheel 26 at all engaging positions, or I may use a combination of such means. In the illustration the front end of shaft 21 is pivoted in an opening 30 in a front plate, the opening 30 being elongated in a direction radial with wheel 26, and the shaft 21 at this point is urged toward wheel 26 by a spring 31 having its opposite ends hooked into openings 32 in the front plate and having its middle portion bent and under straightening tension beneath shaft 21 adjacent the slot 30. Thus the drive surface of part 25 is urged against and in driving relation with the drive surface of wheel 26, by spring 31, while allowing limited up-and-down movement of the forward end of shaft 21 and cam member 26-25.

When the button 22 and parts attached thereto are turned counterclockwise from the "on" position shown to an inactive or "off" position limited as by a stop indicated at 34 and with the indicator 23 to the left of the scale 24, the end 19 of lever 16 no longer rides on the raised portion at 35 of cam 20 and, hence, lever arm 16 has a position clockwise from that shown, and its end 17 does not press down on 18 and it does not hold contact 6 down against contact 7 such that the switch will be open so far as the sleep switch feature is concerned. It is assumed that the other controls of the switch are such that the switch is open. Also the sector 25 will have moved sufficiently counterclockwise from the position shown to disengage the driving connection between 25 and 26. Now, to close the switch for a predetermined time interval so that it will open automatically, shaft 21 is turned clockwise by button 22 so that cam surface 35 rotates lever 16 counterclockwise, contact arm 6 is bent downward against its own resiliency to close the switch, and the drive surface of sector 25 engages wheel 26. During this manual closing of the switch, the sector 25 after engagement with wheel 26 slips on wheel 26 because wheel 26 is constrained by its geared connection with the clock train to rotate slowly at a speed determined by the gear ratio. However, as soon as button 22 is released, and is no longer manually restrained, the connection between 25 and 26 becomes a driving connection and wheel 26 slowly drives sector 25 and the other parts connected to shaft 21 in a counterclockwise direction at a constant rate until the parts are driven to the idle or "off" position and the switch opens.

For the purpose described, the rate of rotation of shaft 21 by the clock is made such that the scale gradations at 24 represent 15 minutes each, and the device is arranged to provide for a timing operation up to one hour. Thus, in Figs. 1 and 4, the position of indicator 23 indicates that in one-half hour the clock will move the sleep switch control features to an idle position and permit the switch to open so far as this control is concerned. When the sleep switch timing feature is in operation, the switch closing time may be extended or reduced by a corresponding manual adjustment by button 22.

The connection between 25 and 26 slips or acts as a positive friction drive, depending upon whether shaft 21 is manually restrained or moved as in a setting operation, or is left free to rotate.

It will be noted that the driving surface of sector 25 is not perfectly circular but has a number of shallow scallops or detents therein. These detents are sufficiently shallow that they do not interfere with either the friction clutch slipping action during manual adjustment or the positive friction drive during a timing operation, since it will be evident that the spring 31 retains sector 25 pressed against wheel 26 at all times, except when the parts are in the idle condition. The detents are, however, sufficiently definite and spaced that as the shaft 21 is manually turned by button 22, there is a distinct variation in the turning force required such that the turning operation may be stopped at any one of the detent points by feel. Thus, as a detent point on sector 25 approaches contact with wheel 26, the manual turning force required is less than that required to move sector 25 away from such detent contact point so that in making a manual adjustment, the sector 25 tends to stop at the positions where the detents 36, 37 and 38 engage the wheel 26 such that a person can easily adjust the time setting to any one of such detent contact points by feel. In the example given, these contact detent points have been positioned at the 15, 30, and 45 minute time adjustment positions. The full hour adjustment may be made by feel by providing an upper limit stop indicated at 39 for such adjustment point. Thus, a person in the dark or without looking at the scale 24, can adjust the time for automatic switch operation to approximately the desired value by feel. The 15, 30, 45 and 60 minute adjustments can be made exactly, and a reasonably close approximation adjustment can be made for intermediate time intervals. The ability to make these adjustments by feel is particularly desirable for the sleep switch application described, and also for blind persons.

It will be noticed that in forming the detent surface of 25, the slopes into a detent point such as the point 38 have been made steeper and shorter at the left side than on the right side of the detent points. Thus the steeper and shorter slopes face toward the trailing or left side of the driving wheel 25, so that in a normal setting operation by rotation of the sector 25 clockwise manually, the more abrupt or steeper slope is encountered in moving a detent point past the contact point of driving wheel 26. During this setting operation no friction driving action is required, and ample manual force is available to slip the engaging surfaces. On the other hand, when the sector 25 is being rotated counterclockwise by the clock in a friction driving, timing operation, only the more gradual slope is encountered in driving a detent point past wheel 26 and no slippage occurs. While the amount and differences in slope represented are not very critical, a difference such as indicated is to be preferred because by so doing the detent "feel" in setting is emphasized while obtaining a high factor of safety against slipping and the least variation in load on the clock driving motor during a sleep switch timing action.

It will now be apparent that I have provided a simple, low-cost, reliable and sturdy control device in which the part 25-35 can be a stamp-

ing, and that it serves with wheel 26 as a friction clutch, a friction drive, and as a setting adjustment detent.

In accordance with the provisions of the patent statutes I have described, the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States is:

1. A combined clutch and friction drive comprising a wheel adapted to be continuously driven in a given direction, a manually adjustable rotary shaft having an axis of rotation substantially parallel to the axis of rotation of said wheel, a sector-shaped member fixed on said shaft and having a generally circular periphery rotatable into and out of frictional driving engagement with the periphery of said wheel, the peripheral engaging surface of said sector-shaped member having spaced shallow depressions forming setting gauging detents along its engaging surface, resilient means for maintaining the engaging surfaces in contact in all rotary engaging positions, and means for manually rotating said shaft to establish and adjustably set said frictional driving engagement relation, the engaging surfaces slipping during such setting and when not manually restrained said shaft is driven by said wheel through the adjusted engagement range of operation of said parts without slippage.

2. A combined clutch and friction drive comprising a wheel adapted to be driven in a given direction at constant speed, a shaft to be driven thereby, a sector-shaped clutch member secured on said shaft having a generally circular peripheral surface rotatable into and out of frictional driving engagement with said wheel, the engaging surface of the sector-shaped clutch member having uniformly spaced shallow detent depressions along its periphery, means resiliently maintaining the surfaces of said wheel and clutch member in firm contact with each other when engaged, and means for manually rotating said shaft for the purpose of rotating the sector-shaped clutch member thereon into driving engagement with said wheel and setting the clutch member to any desired rotary engaging position with said wheel, the engaging surfaces slipping during such adjustment, said wheel then driving said clutch member to disengaging position without slippage when said shaft is not manually restrained.

3. A friction drive and clutch mechanism comprising a rotatively mounted driving wheel and a rotatively mounted sector-shaped clutch mem-

ber having a generally circular peripheral surface rotatable into and out of driving engagement with the periphery of said wheel, said clutch sector having shallow detent depressions spaced along its engaging surface, means for resiliently maintaining the engaging surfaces in firm contact when in driving relation, means for continuously rotating said driving wheel in a given direction at a predetermined speed, and means for manually rotating said clutch member from disengaging to engaging position with respect to wheel and to set their relatively rotary engaging positions, their engaging surfaces slipping during such manual setting operation, said wheel then driving said clutch member to disengaging position without slippage when the clutch member is not manually restrained, the side slopes into the shallow peripheral detent depressions of said clutch member which face toward the trailing side of the driving wheel being shorter and steeper than the other side slopes into such depressions.

4. A combined friction drive and setting clutch for a time and manually controlled "on," "off" operating device comprising a wheel driven at a constant speed in a given direction, a rotary control shaft, a sector mounted on said shaft positioned such that its periphery may be rotated into and out of driving engaging relation with the periphery of said wheel, manual means for rotating said shaft from an "off" control position where its sector is disengaged from said wheel to an "on" control position where its sector is engaged in driving relation with said wheel and adjusting said sector to any desired "on" engaging position with said wheel, such manual adjustment being accompanied by slippage between the contacting surfaces of wheel and sector, shallow detents uniformly spaced along the peripheral engaging surface of said sector for the purpose of enabling the "on" time setting position of said sector to be determined by feel during the manual setting operation, and resilient means for maintaining the contacting surfaces of wheel and sector in driving relation in all engaging positions, said shaft and sector being driven to an "off" position in a time period determined by the "on" setting adjustment and beginning as soon as said shaft is manually released after an "on" setting operation.
